UNITED STATES PATENT OFFICE.

GRACE FORD GHOLSON, OF EVANSTON, ILLINOIS.

SOAPING DEVICE FOR WASHBOARDS.

1,178,514.

Specification of Letters Patent.

Patented Apr. 11, 1916.

Application filed April 9, 1915. Serial No. 20,302.

To all whom it may concern:

Be it known that I, GRACE FORD GHOLSON, a citizen of the United States, residing at Evanston, in the county of Cook and State 5 of Illinois, have invented new and useful Improvements in Soaping Devices for Washboards, of which the following is a specification.

This invention relates to soaping devices 10 for washboards, and it has particular reference to a device for supplying liquid soap to the clothes that are to be washed.

One object of the invention is to produce a container made of rubber or anal- 15 ogous material which may be conveniently connected with the frame of a washboard for the purpose of supplying liquid soap, said container being provided with discharge openings which are normally closed, the 20 closing of said openings being due to the resilient action of the material of which the bag is constructed.

A further object of the invention is to produce a simple and improved construction 25 whereby the container may be conveniently connected with the frame of a washboard.

A further object of the invention is to produce a container of simple and improved construction for the purpose indicated.

30 With these and other ends in view which will readily appear as the nature of the invention is better understood, the same consists in the improved construction and novel arrangement and combination of parts 35 which will be hereinafter fully described and particularly pointed out in the claim.

In the accompanying drawing has been 40 illustrated a simple and preferred form of the invention, it being, however, understood that no limitation is necessarily made to the precise structural details therein exhibited, but that changes, alterations and modifications within the scope of the claim may be resorted to when desired.

45 In the drawing,—Figure 1 is a front view of a washboard to which the invention has been applied. Fig. 2 is a sectional detail view, enlarged, taken on the line 2—2 in Fig. 1. Fig. 3 is a sectional detail view taken 50 on the line 3—3 in Fig. 2. Fig. 4 is a sectional detail view taken on the line 4—4 in Fig. 1.

55 Corresponding parts in the several figures are denoted by like characters of reference.

The washboard to which the invention has

been applied comprises the stiles or side members 15 which are spaced and connected by means of cross bars 16, 17. The side members are also connected together at their upper ends by means of a top or cap piece 18 which is detachably connected with the side members by suitable connecting means, such as bolts 19 and wing nuts 20. The rubbing face 21 which may be made of glass, 65 corrugated zinc or other material is framed between the side members 15 and the cross bars 16, 17. The cross bar 17 and the cap piece 18 are provided in their opposed faces with grooves 22, 23, as clearly seen in Figs. 70 2 and 4, and the stiles or side members are provided in their opposed faces with grooves 24 that extend between the cross bar 17 and the cap piece 18, said grooves being clearly indicated in Fig. 3. The cap piece 18 is also 75 provided about midway between its ends with an aperture 25, as best seen in Fig. 2.

The bag or container C which is made of rubber or other suitable material, such as composition containing rubber, is of sub- 80 stantially rectangular shape and of a size which will enable it to fit in the space bounded by the cross bars 17, 18 and the upper grooved portions of the side members 15. Said bag is provided with a filling tube 85 26 extending through the aperture 25 of the cap piece and adapted to receive a cap or closure 27 preferably having threaded connection therewith. The sides of the bag or receptacle are provided with ribs 28 engag- 90 ing the grooves 24 in the stiles or side members of the frame; the bottom portion of the bag has a rib 29 engaging the groove 22 in the cross bar 17, and the top portion of the bag is provided with a rib 29 engaging the 95 groove 23 in the cap piece 18. The bag or receptacle is additionally supported by means of a panel 30 which is assembled with the frame members of the washboard by 100 engaging grooves 31 in said frame members. The upper face of the bag is provided near the lower edge with a series of small bosses or projections 32, each having a narrow slit 33 which is normally closed by the resilient action of the material of 105 which the bag is constructed.

In practice, the bag or receptacle may be readily assembled with the washboard by temporarily removing the cap piece 18, as well as the cap or closure 27, thus enabling 110 the bag to be positioned between the cross bar 17 and the upper ends of the side mem-

- bers 15, after which the cap piece 18 is re-
stored to position, when the cap or closure
27 may be applied, the bag having been first
filled with liquid soap. When clothes are
5 being washed, the pressure of the hands
exerted at each down stroke will slightly
compress the bag or receptacle, causing a
portion of its contents to be expelled
10 through the slits 33, the walls of which will
immediately close together when the pres-
sure is interrupted. By regulating the de-
gree of pressure, the quantity of liquid soap
supplied at each stroke may be gaged or
regulated.
- 15 It will be seen from the foregoing de-
scription, taken in connection with the
drawing, that I have produced a very simple
and efficient device whereby liquid soap may
20 be supplied to garments that are being
rubbed on a washboard, the said device be-
ing inexpensive, easily applied and of such
a nature that the quantity of soap supplied
may be easily and accurately regulated.

Copies of this patent may be obtained for five cents each, by addressing the "Commissioner of Patents
Washington, D. C."

Having thus described the invention,
what is claimed as new, is:—

25 A washboard comprising a frame, a cross
bar, secured to the upper end of said frame
below its top, a corrugated member secured
in said frame and to said cross bar, said
cross bar being beveled transversely, a me-
tallic soap container removably secured to
30 said frame and resting on said cross-bar,
a plurality of integral teats formed upon
said container, and each having a slit com-
municating with said container, said cross
bar forming a bridging surface inclining
35 from said corrugated member toward said
teats, said teats projecting forwardly of
said cross bar, and a filler device on said
container.

40 In testimony whereof I affix my signature
in presence of two witnesses.

GRACE FORD GHOLSON.
